CORSELET

Harry Jay Dubner, New York, N. Y.

Application September 14, 1937, Serial No. 163,777

10 Claims. (Cl. 2—27)

This invention relates to garments and has particular reference to devices of the type used by stout women for compressing the abdomen and diaphragm.

5 One object of the invention is to provide a garment of the character described wherein an inner belt for an outer restraining portion of the garment is secured around the body at a much higher tension than that of the outer portion, 10 and the central part of the front section of the outer garment portion being subjected by the belt to the much higher tension mentioned to shift excess flesh laterally so as to be retained by lower tension lateral parts of the outer section 15 above and below the belt.

In respect to specific function, the belt portion of the garment serves to powerfully draw in the abdomen and diaphragm. This tends to form a bulge or roundness at the front center of the belt 20 portion. Moreover, parts of the excess flesh escape from the belt portion, especially upwardly. Thus unevenness in body contour results. Yet the belt may not be too wide up and down because undue discomfort would be caused. Even 25 with my belt which covers only the abdomen and diaphragm, an elastic portion is highly desirable to allow for some variation as in standing up and sitting down.

Reference may be made to U. S. Patent No. 30 2,089,950 for Corselet, which is owned by me, and which patent will serve to illustrate further the type of garment to which the present invention relates.

The main problem for success in a garment of 35 this character is to avoid the irregular body contour due to the bulge at the belt, and especially due to bulges produced above the belt by the action of the belt itself. Numerous attempts have been made by corset experts to obtain a 40 smooth uniform body contour without undue discomfort to the wearer, but have not been successful.

These difficulties I have solved by improvements in the garment, in which the belt portion 45 is separately secured, as practically it must be, for the high tension desired. Further, in the garment to which my improvements relate, the outer garment portion is preferably wholly or substantially inelastic and is accurately shaped 50 to correctly fit the body. In such a garment, I provide gusset-like means for interconnecting the belt portion with the outer garment portion instead of directly interconnecting these portions. Preferably, the gusset-like means includes at 55 least one elastic portion. Desirably, the elastic

part of the belt portion is located at any point intermediate of the spaced gusset means. With this principle, greater freedom of movement is permitted, and the belt portion tensions the gusset means and hence the intermediate part of the 5 outer garment portion. This intermediate or front section of the outer garment portion may thus be at a considerably higher tension than the adjacent lateral parts of the outer garment portion, and is thus quite flat so as to even out the 10 contour of the body. Also the tension of this section varies with that of the inner belt. And yet, because this section is itself relatively non-elastic, its original body shaping fit is maintained.

The excess flesh that escapes the belt may 15 thus be comfortably retained by the lateral parts of the outer section above and below the belt. The central part of the outer section not only shifts the excess flesh, but aids the belt in its tension and produces the flattened appearance. 20

Hence the outer garment portion or the front section thereof referred to may be denoted the body flattening part, in contradistinction to the belt portion which may be denoted as the body compressing part. Further, it may be observed 25 that within the broad scope of the invention, any elastic element may be designated a yielding or an adjusting means, so that the latter may include adjustable lacing, which, however, is less 30 advantageous as it may require a change in tensioning from time to time.

Another object of the invention, therefore, is the provision of a garment having an inner high tension belt and an outer flattening garment part 35 whose front section is connected to the belt so as to be subject to a higher tension than adjacent lateral parts of the outer garment part, above and below the belt, and with the tension on said front section being less than or equal to that of said belt. 40

Another object is to furnish such a garment wherein the outer garment part may assume a conformation different than that of the belt, to flatten bulges that may be caused by the belt, with the outer garment part being tensioned by 45 the belt.

Another object of the invention is to provide a garment including an abdomen and diaphragm compressing high tension inner belt having an adjustable portion accommodative to body 50 changes, and an outer body-flattening, relatively non-stretching low-tension garment part whose front section is connected at its ends to the front part of the belt, one of the connections comprising an adjustable or elastic element extending 55

between the belt and outer garment part for transmitting tension from the former to the latter.

Another object of the invention is to furnish a garment having an inner belt according to an improved arrangement such as will tend to cause separation of the breasts.

A further object of the invention is to provide a garment of the character described having few and simple parts, and which is durable, reliable and efficient in use.

Other objects and advantages of the invention will become apparent as the specification proceeds.

With the aforesaid objects in view, the invention consists in the novel combinations and arrangements of parts hereinafter described, in their preferred embodiments, pointed out in the subjoined claims, and illustrated in the annexed drawing, wherein like parts are designated by the same reference characters throughout the several views.

In the drawing:

Figure 1 is an inside plan view of the garment laid out in open position, with parts removed.

Fig. 2 is a sectional view on the line 2—2 of Fig. 1.

Fig. 3 is a similar sectional view but with the parts tensioned to generally correspond to actual use.

Fig. 4 is a fragmentary view with parts removed of a modified form of the invention.

Figs. 5 and 6 are sectional views taken respectively on the lines 5—5 and 6—6 of Fig. 4.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a garment embodying the invention. The same may include an outer or main garment part 11, and an inner belt 12 therefor. The outer garment is adapted to completely encircle the body of the wearer from the bust to the hips, including these parts. Hence it may comprise a back part 13 that is stiffened as by boning 14. To one end of the back part is connected the front part 15, the other ends being releasably interconnected along the edges 16, 17 as by hooks, lacing, or the like.

The inner belt 12 is connected at one end at 18 to the outer garment part 11 adjacent to the junction between the front and back garment parts. Its other end 19 may be releasably secured to the back part 13 as by means of an inner flap portion 20. The latter may be connected at 21 to the back 13, and its free edge 22 is connectible by hooks or the like to the said edge 19. In up and down width, the inner belt 12 is sufficient to cover the diaphragm and abdomen, and is consequently substantially less in length than the outer garment part. For instance, the latter extends upward at 23 above the inner belt and may even include a brassière portion 24. Likewise, the outer garment part may extend below the belt 12 so as to reliably embrace the hips. If desired, the belt 12 may have bottom ex-

tensions such as 25 to which garters may be secured.

It is important to note that a primary characteristic of the outer garment part 11 is that it is cut, worked and shaped to accurately fit the individual wearer when his body is tensioned by the inner belt 12. For this purpose suitable seams, elastic gores, shapes of edges as at 16, 17 are provided to furnish different capacities at different points of the garment for a form fitting action with the outer garment part 13 being under tension. Elastic elements, wherever provided, as at 26, 27, are distinctively hatched with horizontal lines. Fold parts as at 28, 29 are indicative of slack that is provided for desired body fitting conformation. Other slack or elastic elements may be furnished in the outer garment part as may be necessary.

However, the front section 15 of the outer garment part, especially the generally central upright part 30 of the front section 15, is relatively or wholly inelastic, since this part is subject, as hereinafter described, to considerable tension and deformation, and must maintain a set position to flatten out or conceal bulges that may be caused by the high tension inner belt 12.

The inner belt 12 operates under high tension and hence is preferably separately attached around the body as at the edges 19, 22. Thereafter the outer garment is secured at lesser tension at the edges 16, 17.

Due to the high tension of the inner belt 12, it preferably includes an elastic element 31 that may extend from the upper to the lower edge thereof. The material of this elastic element 31 has limited stretchability, because its fabric is constructed with non-stretching threads which come into action when the elastic threads have been stretched to a predetermined extent. The elastic element 31 permits accommodation to the wearer for standing and sitting positions, and other body changes.

The back part 13 of the outer garment part may be subject to the high tension of the inner belt 12, but this is immaterial, because there is relatively little excess bulge producing flesh at the wearer's back.

The invention provides means whereby the limited elasticity of the inner belt 12, as above described, is utilized as a means for increasing the tension on the central upright part 30 of the front section 15 above that of the adjacent parts of said section 15. Thus one or more gusset elements 32, 33 may each be connected at one edge 34 to the inner belt, and at the opposite edge 35 to the front section 15. Preferably, the arrangement is such that the edges 35 are closer to each other than the edges 34. Thus these gussets 32, 33 are narrow, upright spaced strips which normally lie flatwise between the inner belt and the section 15, but may also be referred to as converging toward each other from the inner belt toward the outer section 15. The lines of stitching at 35 more clearly define therebetween the upright nonstretching central section 30 of the outer garment. Because of this non-stretching quality of the section 30, it is transversely tensioned by the inner belt acting through elastic means, one or both of the gussets 32, 33 consisting of elastic material. If desired, the gusset 33 may be omitted so that the tension acts between the gusset 32 and the stitching at 35.

By choosing material of desired elasticity for the gussets 32, 33, any desired tautness may be

produced in the part 30, in excess of that caused by the fastening at 19, 22. Hence the tension at 30 may be equal to but is preferably somewhat less than the tension of the inner belt 12. The 5 latter may have boning as at 36 tending to straighten or flatten out any resulting bulge, and the part 30 serves to further produce the appearance of flatness and uniformity.

It is noted that the section 30 may have some 10 slack therein as at 31, and the section 15 may have some slack as at 38 between the stitching 18 and 34, in the nontensioned position of the garment. In lieu of slack, adjusting or elastic means may be provided.

15 It will now be seen that the invention is characterized by a front garment section 15, having lesser tension than the inner belt, and having a central higher tension region produced by the inner belt. In other words, the regions of the 20 front section 15, lateral to the central section 30 may have a lesser tension than the section 30. This may be effected by providing a sufficient slack at 38, and by suitably arranging the length of the garment between the edges 16, 17. 25 Hence the excess flesh which escapes the inner belt 12 upward and downward is forced laterally by the central section 30 toward the upper lateral regions at 39, 40 and the lower lateral regions at 41, 42 with resulting flatness at the front.

30 In Figs. 4 to 6 is shown a garment 45 which is generally like the garment 10, except that the inner belt 12a is formed with a central upward extension 46 which is free of the outer section 15 except that it is connected at its upper end 35 at 47 to the top of the section 15. Being otherwise free of the latter, the section 46 aids in separating the breasts. This result may be aided by securing a pad element or strip 48 to the part 46 to lie between the latter and the front 40 section 15, said pad element being secured at 47 and 49 to bridge the space between the body and the brassière, the latter being held outward by the bust. The elastic 31a is somewhat differently positioned, but this is immaterial.

45 I claim:

1. A garment including an outer or main garment portion and an inner belt portion, the garment portion comprising a front section and a rear section and being attachable around the wearer's body so as to extend between and to cover the bust and the hips, the belt portion being adapted to cover only the abdomen and diaphragm and extending along and being connected near its opposite ends to the said front section, the belt portion having an elastic part and being attachable around the body under high tension, the said connections including gusset like elements each being connected at spaced points to the belt portion and front section, said elastic part being located between and cooperating with the elements so that stretching of the elastic part causes said elements to exert a stretching force on the adjacent central part of the front section, said elements operatively 50 extending to the top edge of the belt portion, and at least one of said elements being elastic, the adjacent central part of the said front section being relatively nonstretching and having an initial slack portion therein, whereby the said 55 adjacent central part of the front section compresses the body under a tension less than that of the belt portion and forces excess flesh laterally to be retained by lateral parts of said front section, which lateral parts have less tension than 60 the adjacent central part.

2. A garment including an outer garment portion comprising a front section and a rear section and having means for attachment thereof around the wearer's body so as to extend between and over the bust and hips, an inner belt adapted to cover only the diaphragm and abdomen, said belt comprising a front portion connected at one end at the junction between the front and rear sections of the outer garment portion, said belt front portion extending along said front section 10 and being yieldably connected thereto along spaced upright lines spaced from the first mentioned connection so as to define a central portion of said front section, said belt front portion having an upright take-up element intermediate 15 of the spaced yielding connections, said belt having means for attaching the same under high tension along the wearer's body independently of the attaching means of the outer garment, said yielding connections including at least one gusset- 20 like element interconnecting the belt and outer garment and lying therebetween so that tension on the belt causes stretching of said element and consequent tautness of the said central part of said front garment section, the said central 25 part being relatively nonyielding so as to tautly press upon the body above the belt at a lesser tension than that of the belt and to force excess flesh laterally under said outer garment above the belt, the said central part of the front garment section having initial slack, and the front 30 garment section having initial slack intermediate of the first mentioned connection and the second mentioned connections.

3. A garment for stout women including means 35 comprising an outer garment member having a front section, and an inner belt member, said members coacting with each other so that the belt member is secured around the body separately of the outer garment member, the front part of 40 the belt being connected along spaced upright lines to the front section up to the upper edge of the belt, the garment member being shaped to tightly fit the wearer's body over the attached belt and the portion of the garment member intermediate of and above the said lines of connection being nonstretching, the belt member having a yielding portion between said lines of connection and extending to the top edge of the belt member, and at least one of the said connections 45 including a strip of elastic material connected at one edge to the belt member and at an opposite edge to the garment member and lying flat between the members to cause the belt to render 50 taut the central part of the front section.

4. A garment including an outer fitted garment member, a yielding inner belt member, the latter being secured around the body at a substantially higher tension than the garment member, means connecting the belt member to the front of the garment member along spaced upright lines, said means including elastic gusset elements lying between the members and serving to hold taut the intermediate part of the garment member to reduce bulging at the belt.

5. A garment including an outer garment member tightly fitted to the body under the tension of an inner belt, an inner belt having a predetermined limited elasticity, the inner belt being operatively secured around the body at a substantially higher tension than the garment member, the latter extending above the belt, means interconnecting the belt and the front of the garment member along spaced upright lines, at least one of the connections including an elastic gusset ele- 70 75

ment extending up to the top edge of the belt, said element being connected along opposite edges to the belt and garment member respectively and serving to hold taut the part of the garment member intermediate of the lines of connection to cause the excess flesh above the belt to be pressed laterally under the garment member into regions of lesser tension.

6. A garment according to claim 5, wherein the front of the garment member is nonstretching to maintain the form fit of the garment and to substantially increase the tautness above the said intermediate part thereof.

7. A garment according to claim 5, wherein the garment member includes a brassière portion and the belt is provided with a top extension forming a bust separating member that extends to the top of the brassière portion and is secured at said top, said extension being otherwise free of the brassière so as to drop in between the breasts and to permit freedom of relative movement between the belt and the garment member.

8. A garment for stout women including means comprising an outer garment member shaped to fit the wearer's body, and an inner belt member, said members coacting with each other so that the belt member is secured around the body separately of the outer garment member and at a substantially higher tension than the latter, the front part of the belt member being connected along spaced upright lines to the garment member, said means having a yielding portion located so as to permit relative expanding movement as between those parts of the outer garment member and inner belt member which lie between said lines of connection, whereby the inner belt member serves to tension the front part of the outer garment member about the wearer.

9. A garment for stout women including means comprising an outer garment member shaped to fit the wearer's body, and an inner belt member,

said members coacting with each other so that the belt member is secured around the body separately of the outer garment member and at a substantially higher tension than the latter, the front part of the belt member being connected along spaced upright lines to the garment member, the garment member being shaped to tightly fit the wearer's body over the attached belt, the belt member being constructed so as to be expandible between said lines of connection, and at least one of the said connections including a strip of elastic material connected at one edge to the belt member and at an opposite edge to the garment member and lying flat between the members to cause the belt to render taut the front part of the outer garment member.

10. A garment for stout women including means comprising an outer garment member shaped to fit the wearer's body, and an inner belt member, said members coacting with each other so that the belt member is secured around the body separately of the outer garment member and at a substantially higher tension than the latter, the front part of the belt member being connected along spaced upright lines to the garment member, the garment member being shaped to tightly fit the wearer's body over the attached belt, the belt member being constructed so as to be expandible between said lines of connection, and at least one of the said connections including a strip of elastic material connected at one edge to the belt member and at an opposite edge to the garment member and lying flat between the members to cause the belt to render taut the front part of the outer garment member, said garment member including a brassière portion, said inner belt having a top extension forming a bust separating member secured at its top to the brassière portion and being otherwise free of the latter.

HARRY JAY DUBNER.
